UNITED STATES PATENT OFFICE

130,222

DESIGN FOR A SCRAPER ATTACHMENT FOR HANDLES FOR BROOMS AND ANALOGOUS ARTICLES

Julius H. Boutte, New Iberia, La.

Application March 25, 1941, Serial No. 99,878

Term of patent 7 years

To all whom it may concern:

Be it known that I, Julius H. Boutte, a citizen of the United States, residing at New Iberia, in the parish of Iberia and State of Louisiana, have invented a new, original, and ornamental Design for a Scraper Attachment for Handles for Brooms and Analogous Articles, of which the following is a specification, reference being had to the accompanying drawing, forming part thereof.

attachment for handles for brooms and analogous articles, showing my new design.

I claim:

The ornamental design for a scraper attachment for handles for brooms and analogous articles, as shown.

JULIUS H. BOUTTE.
